DESIGN FOR A HAT

G. Howard Hodge, New York, N. Y.

Application July 25, 1944, Serial No. 114,553

Term of patent 3½ years

(Cl. D3—13)

To all whom it may concern:

Be it known that I, G. Howard Hodge, a citizen of the United States of America, residing in New York city, county of New York, and State of New York, have invented a new, original, and ornamental Design for a Hat, of which the following is a specification, reference being had to the accompanying drawing, forming part thereof.

Fig. 1 is a side perspective view of a hat showing my new design, and

Fig. 2 is a perspective view of the side opposite that shown in Fig. 1.

I claim:

The ornamental design for a hat, substantially as shown.
